UNITED STATES PATENT OFFICE.

WILLIAM H. KELLER AND ALBERT SCHINKEZ, OF GRAND HAVEN, MICHIGAN,
ASSIGNORS TO KELLER PNEUMATIC TOOL COMPANY, OF GRAND HAVEN,
MICHIGAN, A CORPORATION OF MICHIGAN.

PERCUSSION-TOOL.

1,387,493.

Specification of Letters Patent. Patented Aug. 16, 1921.

Application filed June 17, 1918. Serial No. 240,429.

To all whom it may concern:

Be it known that we, WILLIAM H. KELLER, a citizen of the United States, residing at Grand Haven, in the county of Ottawa and State of Michigan, and ALBERT SCHINKEZ, a subject of the Emperor of Austria, residing at Grand Haven, in the county of Ottawa and State of Michigan, have invented certain new and useful Improvements in Percussion-Tools, of which the following is a specification.

The invention relates to percussion tools and more particularly to rivet set retainers therefor; and the object of the invention is to provide a device of a very practical character which will effectively retain a rivet set in operative position in the forward end of a tool body and which is readily operable without removal from the body to release the rivet set when desired.

The object of the invention thus generally stated, together with other and ancillary advantages, is attained by the construction and arrangement illustrated in the accompanying drawings, forming part hereof, in which Figure 1 is a longitudinal sectional view through the forward end of a pneumatic hammer embodying the features of our invention, showing the parts in retaining or closed position, the view being taken on line 1—1 of Fig. 2. Fig. 2 is a front end elevation of the tool with the parts in the position shown in Fig. 1. Fig. 3 is a longitudinal sectional view through the forward end of a tool with the parts in releasing or open position, the view being taken on line 3—3 of Fig. 4. Fig. 4 is a front end elevation of the tool with the parts in the position shown in Fig. 3.

In the drawings, 1 indicates the body of a pneumatic hammer having a rivet set 2 in its forward end. The hammer body may be of any preferred construction, and the rivet set comprises a shank 3, a head 4, and an intermediate flange or shoulder 5. The hammer body is provided with a bore 6 for the shank 3 and the inward movement of the set in the body is limited by the shoulder 5 abutting against the forward end of the body 1.

The retainer is adapted to limit the outward movement of the rivet set in the body and comprises a plurality of members 7,

three being shown herein, arranged to be clamped upon the tool body by means of an annular ring 8 which is held in position by means of a snap spring 9 carried by one of the members 7.

Each of the members 7 is arcuate in form and its forward end has formed thereon a flange or dog 10 projecting inwardly into the path of movement of the shoulder 5 of the rivet set so as to limit the outward movement of the latter in the body. Preferably the members 7 are made of such size that when fitted together upon the body they substantially surround it and the rear ends of the members are each provided with an inwardly projecting dog 11 arranged to engage, a short distance rearwardly from the forward end of the tool body, in an annular groove 12 provided in the periphery thereof. The forward end of the tool body is tapered as at 13, and the members 7 are correspondingly shaped so as to bear upon such tapered surface 13 while their dogs 10 are disposed in the path of movement of the shoulder 5 on the rivet set. Rearwardly of the tapered surface 13 at the forward edge of the groove 12 the body has an annular bearing surface 14 upon which the members 7 bear near their rear ends with the inner surfaces of the dogs 11 raised slightly out of engagement with the body (Fig. 1). It will be seen that the annular surface 14 serves as a fulcrum upon which the members 7 are arranged to rock and when the rear ends of the members 7 are moved radially inwardly until the inner surfaces of the dogs 11 lie flat against the bottom of the groove 12, the dogs 10 at the forward ends of the members are in the position shown in Fig. 3, out of engagement with the rivet set.

In order to rock the members 7 and hold them in either their open or closed position, that is to say, either in position to retain the rivet set or in position to release the rivet set, we have provided the annular ring 8 surrounding the members 7 and movable longitudinally relative thereto. On its opposite ends the ring is provided with in-turned portions or bosses 15 and 16, respectively, and the outer surfaces of the members 7 are dished or concaved in their central portions to provide at the opposite ends of the members raised annular bear-

ing surfaces 17 and 18 for the inner surfaces of the inturned portions 15 and 16. The forward ends of the concaved surfaces of the members 7 terminating in the raised surfaces 17 form cam surfaces 17^a with which the forward end of the ring 8 slidably engages as it is moved forwardly to force the forward ends of the members inwardly; and annular shoulders 19 and 20 are provided at the forward and rear ends respectively of the members to limit the longitudinal movement of the ring 8.

The parts are so proportioned and arranged that when the boss 15 at the forward end of the ring rests upon the bearing surface 17, the boss 16 at the rear end of the ring bears upon the members 7 forwardly of the annular surface or fulcrum 14 on the body. At their forward ends the concaved surfaces of the members are made deeper than at the rear ends thereof so that the cam surface 17^a of each member is made somewhat abrupt. By this construction when the ring is moved rearwardly from the position shown in Fig. 1 to move the boss 16 at the rear end of the ring onto the surface 18, rearwardly of the fulcrum 14, the boss 15 at the forward end of the ring is quickly moved off from the surface 17 and the rear ends of the members are forced radially inwardly. When the ring is again moved forwardly the boss 15 rides up upon the cam surface 17^a of the members forcing the dogs 10 inwardly and when the forward end of the ring rests upon the bearing surfaces 17 of the members 7, the dogs 10 are positively held by the ring in their innermost position in the path of movement of the shoulder 5 on the rivet set. Similarly, as the ring is moved to its rearmost position, said members are rocked to move the dogs 10 outwardly, and the dogs 11 inwardly, and when the boss 16 at the rear end of the ring rests upon the bearing surfaces 18 of the members 7, rearwardly of their fulcrum 14, the dogs 11 are held so that their inner surfaces lie flat against the bottom of the annular groove 12. It will be seen that in the relatively short movement of the ring 8 from its foremost to its rearmost position and vice versa, the members 7 are rocked upon the annular bearing surface 14 as a fulcrum to move the dogs 10 either in or out of operative position, but without releasing the dogs 11 from engagement with the body.

The snap spring 9 is adapted to yieldingly hold the ring 8 in either its foremost or rearmost position, as may be desired. To this end the spring is formed of a short piece of spring wire arranged to lie in a groove 21 formed in the outer surface of one of the members 7. Preferably, the forward end of the spring is fixed in the member and its rear end is bent to form a projection or hump 22. In the position of the

parts shown in Fig. 2, it will be seen that the hump 22 engages with the rear end of the ring 8 to hold the ring in its foremost position whereby to retain the rivet set in operative position; and in the position of the parts shown in Fig. 3, said hump engages with the cam surfaces 17^b at the rear end of said ring.

It will be evident that we have provided a retaining device of a very practical character in that it is readily operable from retaining to releasing position or vice versa without necessitating the removal or replacement of any part or parts of the retainer. Thus the operation of replacing a rivet set, in the use of the tool, is greatly facilitated. Furthermore, by reason of the extreme simplicity in construction and arrangement, the cost of manufacture of the device is reduced to a minimum.

While we have herein illustrated and described the invention with considerable particularity, it will be understood that we do not intend to be limited to the construction and arrangement set forth except as may be necessitated by the state of the prior art, for obviously many changes may be made in the device which are within the spirit and scope of the invention.

We claim as our invention:

1. In a percussion tool, the combination with a barrel having a forward tapered end and an annular peripheral groove rearwardly of said tapered end, a tool mounted in said barrel and having an annular flange, a plurality of members fulcrumed on the barrel at the forward edge of said groove and each having at one end a portion projecting into the path of said tool flange and at its other end a dog engaging in said annular groove, a ring for retaining said members upon the forward end of the barrel having annular bosses at its opposite ends arranged to engage respectively with the opposite ends of said members, said ring being of a length less than the length of the members so as to be movable longitudinally relative thereto and said members having recesses in their outer faces between their opposite ends adapted to receive the boss on the forward end of the ring when the ring is moved rearwardly thereof whereby to permit the forward ends of the members to be moved radially outward by the boss at the rear end of the ring engaging with the rear ends of said members.

2. In a percussion tool, the combination with a barrel having a forward tapered end and an annular peripheral groove rearwardly of said tapered end, a tool mounted in said barrel and having an annular flange, a plurality of members fulcrumed on the barrel at the forward edge of said groove and each having at one end a portion projecting into the path of said tool flange and

at its other end a dog engaging in said annular groove, a ring for retaining said members upon the forward end of the barrel having annular bosses at its opposite ends arranged to engage respectively with the opposite ends of said members, said ring being of a length less than the length of the members so as to be movable longitudinally relative thereto and said members having recesses in their outer faces between their opposite ends adapted to receive the boss on the forward end of the ring when the ring is moved rearwardly thereof whereby to permit the forward ends of the members to be moved radially outward by the boss at the rear end of the ring engaging with the rear ends of said members, one of said members having a longitudinal groove therein, and a spring member fixed in said groove and adapted to coact with the boss at the rear end of the ring to hold the latter in either its forward or its rear position.

In testimony whereof we have hereunto set our hands.

WILLIAM H. KELLER.
ALBERT SCHINKEZ.
